(57) **CLAIM**

The ornamental design for an electric hair clipper, as shown and described.

DESCRIPTION

FIG. 1 is a perspective view of the electric hair clipper showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view of thereof; and,

FIG. 7 is a bottom plan view of thereof.

The broken lines in the figures are for the purpose of illustrating portions of the electric hair clipper, which form no part of the claimed design.
